BAG FEEDING AND PACKAGING MACHINE

Daniel Belcher, Everis D. Munson, and Harold V. Kindseth, Minneapolis, Minn., assignors to Bemis Bro. Bag Co., Minneapolis, Minn., a corporation of Missouri

Application June 7, 1940, Serial No. 339,314

8 Claims. (Cl. 226—61)

This invention relates to new and useful improvements in bag feeding and packaging machines and particularly to machines for packaging such commodities as sugar and other pulverized or ground materials.

In recent years, it has become quite common to package sugar in small paper bags. In machines now used for this purpose, the bags are usually manually fed to the machine and the operation of the weighing and filling apparatus is controlled by the operator. In feeding the empty bags to the machine, the operator must open each bag mouth before he can slip the empty bag over or onto the filling spout of the machine, after which he actuates a trip or other control means to cause the filling mechanism to deliver a charge into the empty bag. The filled bag is subsequently manually removed from the filling spout. To thus manually feed the bags to the machine and remove the filled bags therefrom, obviously limits the capacity of the machine and therefore adds to the cost of the packaged commodity. It is therefore highly desirable that means be provided whereby the packaging of such material may be accomplished more expeditiously and economically.

An object of the present invention, therefore, is to provide a machine for packaging sugar and other commodities, which is substantially automatic in operation, the only manual operation required being to place a supply or stack of empty bags in the magazine of the machine.

A further object is to provide a machine comprising a magazine in which the empty bags are placed in superposed relation and means being provided for automatically feeding the bags from the magazine, one at a time, to a filling spout over which the mouth of the empty bag is fitted and secured, delivering a predetermined charge of material into the bag, and subsequently removing the filled bag from the filling spout and depositing it onto a suitable conveyer.

A further object is to provide a bag feeding and packaging machine comprising a magazine for supporting the empty flat bags, and a feeding mechanism being arranged beneath the magazine having means for successively withdrawing the empty bags from the bottom of the magazine, and conveying each bag to a filling spout, means being provided between the magazine and the filling spout for "breaking" the bottom of each bag and subsequently opening the bag mouth, whereby the mouth of the bag may readily be slipped over the filling spout, after which the filling spout is expanded to secure the bag

thereto, and simultaneously the filling mechanism is actuated to cause a predetermined charge of material to be delivered into the empty bag secured to the filling spout.

5 A further object is to provide a magazine for supporting a stack of flat empty bags in superposed relation, having means for engaging the top ends of the lowermost bags supported in the magazine and inwardly pressing said bag ends, 10 whereby the bag bodies are bent downwardly and thereby cause the mouth of the lowermost bag in the magazine to be partially opened to facilitate the entrance therein of a suitable gripper blade which operates to withdraw the lowermost bag downwardly, out of the bottom of the magazine, and move said withdrawn bag into position to receive a charge.

Other objects of the invention reside in the novel construction of the lower portion of the 20 magazine, whereby the lowermost bag therein may readily be removed therefrom; in the means provided for engaging the bag bottom and folding it downwardly with respect to the bag body whereby the bag body may more readily be expanded to its proper shape, when the empty bag is supported on the filling spout and a charge is delivered thereto; in the means provided for opening the bag mouth to receive the filling spout; in the novel construction of the filling 25 spout, whereby it is normally contracted or substantially closed to facilitate insertion into the bag mouth, after which it is expanded and simultaneously swings into position to receive a charge from a weighing hopper, whereby a predetermined charge is delivered into the empty bag; in the provision of the flexible, porous tube which extends downwardly through the filling spout from the hopper of the weighing mechanism and conducts the material into the bag whereby 30 "puffing" of the material from the bag mouth is prevented; in the means provided for removing the filled bags from the machine; in the means adapted to be actuated by each bag for controlling the operation of the material-dumping mechanism, whereby should the bag feeding mechanism fail to deliver an empty bag to the filling spout, during the operation of the machine, the dumping mechanism will not deliver a charge into the filling spout; and, in the simple construction of the various parts of the 35 machine and the arrangement thereof, whereby the machine is very compact and requires little floor space.

Other objects of the invention will appear from the following description and accompanying

drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the drawings:

Figure 1 is an end view of a packaging machine with the invention embodied therein;

Figure 2 is a back view of the machine shown in Figure 1;

Figure 3 is an enlarged detail sectional view substantially on the line 3-3 of Figure 12, with some of the parts omitted, showing the means for opening the bag mouth to permit the gripper blade to enter the bag;

Figure 4 is a detail sectional view showing the bag mouth opener in its normal position;

Figure 5 is a view similar to Figure 4, showing the bag mouth opened to receive the gripper blade;

Figure 6 is a fragmentary sectional view substantially on the line 6-6 of Figure 5;

Figure 7 is a detail sectional view on the line 7-7 of Figure 5;

Figure 8 is a sectional plan view on the line 8-8 of Figure 5;

Figure 9 is a detail sectional view on the line 9-9 of Figure 7;

Figure 10 is an enlarged detail sectional view on the line 10-10 of Figure 2, showing the gripper blade about to withdraw a bag from the magazine;

Figure 11 is a view showing a bag withdrawn from the magazine and also showing the clutch control for the sugar dumping mechanism;

Figure 12 is a front view of Figure 11;

Figures 13, 14, and 15 are fragmentary views showing different steps in the operation of "breaking" the bag bottom whereby the bag body is more readily expanded during the filling operation;

Figure 16 is an enlarged detail sectional view on the line 16-16 of Figure 22, showing the mechanism for opening the bag mouth to receive the filling spout;

Figure 17 is a detail sectional view showing a portion of the means for operating the bag mouth opener;

Figure 18 is a detail sectional view on the line 18-18 of Figure 17;

Figure 19 is a detail sectional view showing the filling spout about to enter the open bag mouth;

Figure 20 is a detail sectional view on the line 20-20 of Figure 26, showing the lower end of the filling spout positioned as shown in Figure 19, and also showing the bag wall gripping jaw on the filling spout in open or inoperating position;

Figure 21 is a view similar to Figure 20, showing the wall of the open bag top secured to the filling spout;

Figure 22 is a detail sectional view of Figure 16 with some of the parts omitted;

Figure 23 is a detail sectional view showing the operating shaft and the parts mounted thereon;

Figure 24 is a rear view of a portion of the machine showing the control member for the dumping mechanism;

Figure 25 is a detail sectional view on the line 25-25 of Figure 24; and

Figure 26 is a detail sectional view substantially on the line 26-26 of Figure 19.

Supporting frame

The main frame of the novel apparatus herein disclosed is shown comprising two side frame members, generally designated by the numeral 2. Each side frame member comprises a lower section 3, an intermediate section 4, and an upper section 5, suitably secured together, as best shown in Figures 1 and 2. The lower frame sections 3 are shown secured together in spaced relation by suitable cross members 6, 7, 8, and 9. The intermediate sections 4 are shown provided with oppositely projecting portions or arms 11 having their terminals tied together by suitable cross rods 12 and 20, the ends of which are suitably secured to the terminals of the arms 11. The upper ends of the upper sections 5 are tied together by a suitable cross member 13 which, as here shown, may be in the form of an inverted channel iron.

To increase the capacity of the machine, we have here shown it provided with two complete bag feeding and filling mechanisms, and the side frame members 2-2 are therefore shown spaced apart sufficiently to accommodate two such complete mechanisms. Obviously, the machine may be provided with any number of such mechanisms without departing from the scope of the invention. When two or more such mechanisms are utilized, a frame member 14 is interposed between adjacent mechanisms. This frame member 14 is mounted upon an upstanding portion 15 provided on the cross member 7 at the rear of the machine, and upon the cross member 9 at the front of the machine. The frame member 14 provides means for supporting the adjacent side walls of the two magazines, subsequently to be described. Suitable bearings 16 are shown provided at opposite sides of the frame for supporting the intermediate portions of the two cross rods 12, best shown in Figure 12.

If only a single operating mechanism is utilized, the frame member 14 is dispensed with and the two side frame members 2 are spaced apart to accommodate the single operating mechanism.

Empty bag supporting means

The means for supporting the empty bags is best shown in Figures 3 to 12, inclusive. As here shown, it comprises a magazine, generally designated by the numeral 17, having spaced side walls 18. As the two operating mechanisms are identical in construction, but one will be described in detail. Each side wall 18 of the magazine has secured thereto a pair of shaft-like studs 19, which are slidably received in suitable bearings 21 provided with adjusting screws 22 for securing the rods or studs 19 in adjusted position. The bearings 21 are secured respectively to the upper frame members 5 and the intermediate frame member 14, as best shown in Figure 12. The magazine side walls 18 are preferably shaped as shown in Figure 10, and are provided adjacent their lower front portions with inwardly extending flanges 23, having inwardly curved portions 24 adapted to be engaged by the outer portions of the top ends of the empty bags supported in the magazine, as best shown in Figure 8. The side walls of the magazine are spaced apart in accordance with the width of the flat bag bodies, as shown in Figure 8, whereby the empty bags may be stacked in the magazine in superposed relation with the outer end portions of the bag

tops engaging the flanges 24 of the side walls of the magazine, as clearly illustrated in the drawings.

The rear portions of the bags are shown supported on inwardly extending shelf members 25 having rear walls 26, as best shown in Figures 3, 8, 9, and 10. The rear bag supporting members or shelves 25 are preferably provided with rearward extensions 21, which are adjustably secured to the side walls of the magazine by suitable bolts 28 received in slots 29 provided in the magazine side walls. The bag supporting members 25 are adjustably supported on the walls of the magazine, whereby the apparatus may be adapted for bags of different lengths. The adjusting screws 22 also provide means whereby the width of the magazine may be varied to suit bags of different widths. It will thus be noted that the magazine is so constructed that it may readily be adjusted for handling bags of different sizes.

The inwardly curved flanges 24 at the front, lower portions of the side walls of the magazine extend downwardly to the lowermost portions of said walls, as best shown in Figure 9, whereby all of the empty bags in the magazine from the bottom to the top of the stack, will be retained in the magazine by the flanges 24 and the supporting shelves 25. To facilitate opening the mouth of the lowermost bag, wedge-shaped elements 31 are provided directly rearwardly of the lowermost portions of the flanges 23, adapted to be engaged by the side edges of the lowermost bag in the magazine, as clearly illustrated in Figures 7, 8, and 9. The elements 31 support the empty bags in the magazine as shown in Figure 9, wherein it will be noted that the bag bodies are slightly bent, which facilitates bending the bag bodies to the positions shown in Figure 5, when the plate element 33 is actuated to inwardly press the bag tops to partially open the mouth of the lowermost bag, as shown in Figure 5.

The machine herein disclosed is particularly adapted for handling bags having satchel bottoms, and in which the bottoms of the empty bags are folded into parallel relation with the bag bodies to facilitate stacking the empty bags. The upper edge of one of the walls of the bag body is also shown provided with a thumb cut, indicated at 32, in Figures 4, 6, and 7, which is customary in the manufacture of bags of this particular type. The thumb cut 32 is shown provided in the bag wall opposite from the wall against which the bag bottom is folded, whereby when the empty bags are stacked in the magazine with the bottoms facing upwardly, as shown in Figures 3, 9, and 10, the thumb cut will be in the bottom wall of each bag as it is supported in the magazine.

Means for partially opening bag mouth

A feature of the invention resides in the means provided for partially opening the bag mouth and successively feeding the empty bags from the magazine. In the apparatus, as shown in Figures 3 to 8, inclusive, the bags are successively fed from the bottom of the magazine, and it is therefore essential that means be provided whereby the mouth of the lowermost bag may be partially opened to facilitate the entrance therein of a suitable gripper member or blade, generally designated by the numeral 30, whereby said gripper blade may engage the bottom wall of the

lowermost bag and withdraw said bag from the magazine.

To thus partially open the mouth of the lowermost bag, a plate element 33 is shown secured to a shaft 34 adjacent the lower front portion of the magazine. The plate 33 is shown provided with a restricted central portion or tab 35 which is inwardly curved, as shown in Figures 4 and 5, and is of such size that it may readily pass through the thumb cut in the bottom wall of the lowermost bag. The shaft 34 is shown mounted for rocking movement in suitable bearings 36 and 37 and has an arm 38 secured thereto, to which one end of a suitable connecting rod 39 is connected, as shown in Figures 3, 4, 10 and 12. When the shaft 34 is rocked from the position shown in Figure 4, to that shown in Figure 5, it will be noted that the plate element 33 will engage the top ends of the lowermost bags in the magazine and push them inwardly and upwardly, whereby the bag bodies will bend, as indicated at 41 in Figure 5, thereby causing the mouth of the lowermost bag to partially open. This results because the plate element 33 does not engage the bottom wall of the lowermost bag but only the top wall thereof, as will be readily understood by reference to Figures 3, 4, and 5.

The plate element 33 is actuated by a cam 42 secured to a tubular member or sleeve 43 mounted on a main operating shaft 44 and non-rotatably secured thereto by a suitable clamping collar 45, best shown in Figures 16 and 23. The cam 42 is adapted to engage a roller 46 mounted on a short arm 47 having one end pivoted to the intermediate frame member 14, as indicated at 48 in Figures 3 and 10. The opposite end of the arm 47 is pivotally connected to the lower end of the connecting rod 39. A suitable spring 49 constantly urges the connecting rod 39 in a direction to hold the roller 46 in peripheral contact with the cam 42, as shown in Figure 12.

Means is provided for preventing the top ends of the lowermost bags in the magazine from sliding upwardly on the inclined surface of the plate element 33, when the latter is moved to its operative position, best shown in Figure 5. Such means is shown comprising a plurality of projections 51 provided on the inner surface of the plate element 33, as shown in Figures 5 and 7. These projections may be integrally formed with the plate element 33 or they may be in the form of rivet heads. They merely function to prevent the top ends of the bags from sliding upwardly on the plate, when said plate is actuated.

Bag feeding means

The means for successively feeding the empty bags from the magazine is best shown in Figures 3, 10, 11, and 16, and comprises the gripper plate 30 which is secured to one end of a tubular connecting rod 52, slidably mounted in a suitable bearing 53 pivotally supported between the end walls 54-55 of a rotary member 56, which, to simplify explanation, will hereinafter be referred to as a drum. This drum comprises the end walls 54-55 and a segmental plate 57 suitably secured thereto, whereby said plate and the end walls 54-55 become, in effect, an integral unit. The end walls 54-55 are provided with suitable hubs 58 which are non-rotatably mounted on the sleeve 43, as best shown in Figure 23.

The lower end of the connecting rod 52, when viewed as shown in Figure 10, is pivotally connected to one end of a forked lever 59 by means

of a split coupling element 61 which, as shown in Figure 16, is secured to the lower end of the connecting rod 52 by a clamping screw 62, shown in Figures 16 and 18. The arm 59 is secured to a short shaft 63 mounted for rocking movement in suitable bearings 64 provided in the end walls 54-55 of the drum 56. A suitable crank arm 65 is secured to one end of the shaft 63 and carries a roller 66 which peripherally engages a cam, generally designated by the numeral 67. The cam 67 is mounted on the sleeve 43 of the main operating shaft 44, and is fixed against relative rotation thereon by a suitable bracket 68, to one side of which the cam 67 is secured by suitable bolts 69, as shown in Figure 22. The opposite side of the bracket 68 is secured to the intermediate frame section 4 of one of the main side frame members 2 of the supporting frame, by suitable bolts 71.

From the foregoing, it will be noted that the tubular connecting rod 52 is carried by the drum 56 and rotates therewith as a unit. For each revolution of the drum 56, the connecting rod will be oscillated about the axis of the pivotal support of the bearing 53 as a result of the roller 66 of the crank arm 65 engaging the periphery of the cam 67. The contour of the cam 67 is such that as the gripper plate 30 approaches the partially open mouth of the lowermost bag, said plate is moved outwardly from the dotted line position shown at A in Figure 3, to the full line position shown in the same figure. Such action of the gripper plate 30 results when the roller 66 moves from the low point 71 of the cam to the relatively higher point 72 thereof, shown in Figure 3. When the roller 66 travels from point 72 on the cam to the high point 73, as shown in Figure 10, the gripper plate is moved into the partially open mouth of the lowermost bag and thence downwardly to the position shown in Figure 10, whereby the bottom wall of the lowermost bag will be clamped between the gripper plate 30 and a gripper pad 14, preferably of rubber. The gripper pad is secured to the end walls 54 and 55 of the drum, as shown in Figure 22. As the roller travels from point 73 on the periphery of the cam to a point 75, no relative movement is imparted to the gripper blade 30, because said portions of the cam's face is concentric. The bottom wall of the empty bag will therefore be firmly clamped to the drum 56, whereby it may be withdrawn from the magazine to the position shown in Figure 16. When the empty bag reaches the position shown in Figure 16, the partially open mouth thereof is opened to a greater extent in order to receive the lower end of the filling spout, generally indicated by the numeral 76.

The means provided for opening each bag mouth, as the empty bags approach the position shown in Figure 16, comprises a plate-like element 77 having a T-shaped head 78 which is adapted to pass through the thumb cut provided in the bottom wall of the lowermost bag, when the gripper plate 30 and opener plate 77 move from the dotted line position shown at A in Figure 3, to the full line position in the same figure. The opener blade is normally seated in a recess 79 provided in the body of the gripper plate 30, whereby when the opener blade 77 is in its normal position as shown in Figures 3 and 5, the upper surface thereof will be substantially flush with the upper surfaces of the gripper plate 30.

The means provided for operating the bag mouth opening blade 77 is best shown in Figure

16, and comprises a push rod 79 mounted for sliding movement in the tubular connecting rod 52 and having its upper end operatively connected to the blade 77 by a suitable link 81. The opposite end of the push rod 79 has a head 82 adapted to engage a button 83 adjustably supported in the arm 84 of a bell crank, generally indicated by the numeral 85. The button 83 is adjustably supported in the arm 84 by suitable screw threads 86, whereby it may be relatively adjusted with respect to the button 82 of the push rod 79. A nut 80 secures the button 83 in adjusted position.

The bell crank 85 is mounted on a stud 87 secured to the end wall 55 of the drum, as shown in Figure 22. A roller 88 is mounted in the other arm 89 of the bell crank 85 and is adapted to engage a cam 91 secured to the adjacent face of the cam 67, as best shown in Figures 22 and 23. The length of the cam face 91 is such that the opener blade 77 is actuated to open the bag mouth as the empty bag approaches the filling spout 76. In Figure 16, the roller 88 of the bell crank 85 is shown about to move out of engagement with the cam face 91, whereby the bag mouth opener blade 77 will assume its normal position, shown in Figure 19, to permit the filling spout 76 to enter the open bag mouth.

Means for "breaking" bag bottom

The machine herein disclosed is particularly designed for handling flat paper bags having satchel bottoms, as shown in Figures 6 and 8. These bottoms are normally disposed in flatwise relation to the bag bodies to facilitate stacking the empty bags in superposed relation and to economize in storage space. The bags are therefore stacked in the magazine with their bottoms disposed in parallel relation to the median plane of the bag bodies, and means is therefore provided for "breaking" or folding the flat bottom of each bag longitudinally upon itself, in order that the bottom of the bag will fill out when a charge of material is delivered into the bag.

The means provided for thus folding or "breaking" the bag bottoms, is best shown in Figures 11 to 15, inclusive, and 19, and comprises a pair of spaced hook elements 92 secured to the lower end of an arm 93 having a hub 94 rotatably supported on the cross rod 12 at the front of the machine, as best shown in Figures 3, 11, and 12. The hub 94 of the arm 93 is mounted between two spacing collars 96 suitably fixed to the rod 12. A bridge member 97 is provided between the spacing collars 96 and has one end of a spring 99 secured thereto, the opposite end of which is connected to an arm 98 provided on the hub 94 of the arm 93. The spring 99 constantly tends to swing the arm 93 inwardly towards the drum 56. An adjusting screw 101 provides means for relatively adjusting the terminals of the spaced hooks 92 with respect to the periphery of the plate 57 of the drum 56.

A pair of arms 95 have their upper ends suitably secured to the cross rod 12 and support at their lower ends, a roller 102, rotatably mounted on a shaft 103. The ends of the shaft 103 are resiliently supported in suitable guide slots 104 provided in the lower ends of the arms 95, as best shown in Figures 3 and 11. Suitable springs 105 are disposed in the slots 104 and constantly urge the shaft 103 in a direction towards the drum 56, as will readily be understood by reference to Figure 11.

The above described mechanism operates in

the following manner; when the lowermost bag in the magazine is pulled downwardly against the clamping block, as shown in Figure 10, the curved plate 57 of the cylinder 56 will engage the body of the bag, as shown in Figure 11, in which position the bag bottom is retained in its normal flat position until the leading edge thereof engages the hook elements 92, as shown in Figure 14. When the leading edge of the bag bottom thus engages the hooks 92, the bottom is folded longitudinally upon itself to the position shown in Figure 15. The folded bottom is next engaged by the roller 102 which exerts a pressure thereon whereby it will retain its folded position, as shown in Figure 19, until the empty bag is positioned on the filling spout 76, as will subsequently be described. A pair of spring fingers 106 are secured to the spacing collars 96 and have their free ends adapted to engage the bag to hold it in contact with the periphery of the drum, as shown in Figures 11 and 13. The fingers 106 also serve to secure the collars 96 to the cross rod 12, as shown in Figure 15.

A suitable device, generally indicated by the numeral 107, is mounted beneath the drum 56 and is adapted to engage the folded bottom of the bag and hold the bag body against the periphery of the drum, as shown in Figure 19, when the bag moves into position to receive the filling spout. The device 107 is preferably shown comprising a pair of brush elements 108 mounted in a cylindrical base member 109 secured in a holder 111 which is preferably adjustably mounted in a slotted arm 112. The arm 112, in turn, is adjustably secured to a bracket 113. The slotted arm 112 provides means whereby the brush elements 108 of the device 107 may be suitably positioned with respect to the periphery of the drum 56.

Bag filling mechanism

The filling spout, generally designated by the numeral 76, comprises a flexible fabricated filling tube 114 having its upper end secured to an annulus 115, which, in the apparatus as here shown, is slidably supported on the cylindrical portion 116 of a suitable hopper 117 of the weighing mechanism, generally designated by the numeral 118. The annulus 115 is shown resiliently supported by suitable springs 119, as will readily be understood by reference to Figure 10. The filling spout further comprises complementary members 121 and 122, between which the lower end of the filling tube 114 is supported. The complementary members 121 and 122 are pivotally supported on the cross rod 20 at the rear of the machine. The member 121 has an enlarged hopper-like portion 123 which supports the intermediate portion of the tube 114, and is provided with hubs 124 bored to receive the rod 20. The member 122 is similarly pivotally supported on the rod 20, and a spring 125 is interposed between the two members 121 and 122 and normally tends to close the lower ends thereof, as shown in Figures 16 and 19, whereby the mouth of an empty bag may readily be fitted over the closed end of the filling spout. The lower end of the flexible tube 114 is preferably secured to the lower end of the spout member 121 by suitable means, not shown, whereby the tube 114 will always retain its proper position within the members 121 and 122. If desired, the lower end of the flexible tube may be secured to both members 121 and 122 whereby when said members are opened to the position shown in Figure 10, the lower end of the tube 114 will be opened to permit the material to pass

freely through the tube from the hopper 117 into the bag or container, shown at 126. In some instances, it may be found desirable not to secure the lower end of the flexible tube 114 to the spout members 121 and 122, but permit it to hang loosely therein. When the lower end of the flexible tube 114 is thus loosely supported within the members 121 and 122, its upper end is preferably secured to the hopper portion 116.

- 10 The flexible tube 114 is constructed of a suitable flexible, porous material whereby air entrained with the material being delivered into the bag through said tube, may escape through the porous material in the wall of said tube and thereby prevent portions of the material from puffing or spouting from the bag top, when a charge is delivered into the bag.
- Means is provided for operating the members 121 and 122, and comprises a crank arm 127 secured to one end of a sleeve 128 rotatably mounted on the rod 20, as shown in Figure 26. The opposite end of the sleeve 128 is secured to the bore of one of the hubs 124 of the spout member 121, whereby the crank arm 127 will operate as a unit 25 with the spout member 121. The horizontal arm 129 has one end pivotally connected to the crank arm 127 and has a slot 131 at its opposite end adapted to receive the sleeve 43 secured on the main operating shaft 44, as shown in Figure 23.
- 30 A suitable roller 132 is secured to the arm 129 and engages the periphery of a suitable cam 133 secured to the sleeve 44 of the main operating shaft, as shown in Figure 23. A suitable spring 134 has one end connected to the arm 129 and 35 its opposite end to a fixed point on the frame, indicated at 135 in Figure 3. The spring 134 constantly urges the arm 129 in a direction to hold the roller 132 in peripheral engagement with the cam 133.
- 40 The cam 133 is provided with a low point 136, as shown in Figure 10. When the roller 132 of the arm 129 is on the high side of the cam, as shown in Figures 3 and 10, the filling spout members 121 and 122 will be in their normal operative positions, as shown in Figure 10. When the roller 132 engages the low point 136 of the cam 133, as shown in Figures 16 and 19, the spring 134 will move the arm 129 inwardly to hold the roller 132 in engagement with the periphery of 45 the cam 133, whereby the hopper or filling spout members 121 and 122 are swung inwardly to bag receiving position, as shown in Figures 16 and 19. Simultaneously, as the members 121 and 122 are swung into bag receiving positions, the lower 50 end of the member 121 will swing into engagement with the lower end of the member 122, whereby the lower end of the filling spout is closed to permit it to readily enter the open mouth of the bag, as best shown in Figures 16 and 19.
- 55 When the spout members 121 and 122 are swung into operative positions, as shown in Figures 10 and 25, the member 122 will engage a resilient stop member 137, carried by an arm 138 secured to the rod 20, as shown in Figure 24.
- 60 The stop member 137 comprises a spring-actuated bolt 139 supported in a housing 141 secured to the lower end of the arm 138. An adjusting nut 142 is provided on the spring bolt 139, whereby the head thereof may be adjusted with respect 65 to the abutment lug 143 provided on the spout member 122. The spring bolt 139 is so adjusted with respect to the spout members 121 and 122, that when said members are in operative positions, as shown in Figures 10 and 25, and the bag 70 is supported thereon, the spring 140 of the spring 75

bolt 139 will be under tension to expand the mouth of the bag.

Means is provided at the lower end of the spout member 121 for gripping a wall of the empty bag to move the bag from the drum 56 into position on the filling spout to receive a charge, as shown in Figures 10 and 25.

The means provided for thus gripping a wall of the empty bag is best shown in Figures 16, 19, 24, and 25, and comprises a jaw 144 secured to one end of a shaft 145 mounted for rocking movement in suitable bearings 146 provided on the spout member 121. The jaw 144 cooperates with a gripping surface 147 on the spout member 121, to grip the walls of the bag, as clearly illustrated in Figures 19, 20, and 21, after which the spout members 121 and 122 are swung into bag filling positions by the cam 133, as shown in Figures 10 and 25.

The means provided for operating the movable jaw 144 comprises an arm 148 having one end slidably engaged with the lower end of a crank arm 149, as shown in Figure 10. The crank arm 149 is pivotally mounted on the rod 20. A slot 151 is provided adjacent the opposite end of the arm 148 to receive the sleeve 43 of the main operating shaft 44, as shown in Figure 23. A roller 152 is mounted on the adjacent end of the arm 148 adapted to be engaged by a cam 153 secured to the sleeve 43, whereby for each revolution of the main operating shaft 44, the arm 148 will be actuated to operate the crank arm 149.

The crank arm 149 is rigidly mounted on the hub of a short arm 154 which is rotatably mounted on the rod 20, as best shown in Figure 26. The arm 154 has a link 155 connecting one end thereof to a lever 156 secured to the shaft 145 of the movable jaw 144. A spring 157 has one end connected to the lever 156 and its opposite end to a collar member 158 secured to the rod 20. The spring 157 constantly urges the jaw 144 in a direction to grip the wall of the bag.

Means is provided for retaining the movable jaw 144 in its open position, as shown in Figures 16, 19, and 20, against the tension of the spring 157, when the spout members are moved into position to receive an empty bag, as shown in these figures.

Such means is best shown in Figures 20 and 21, and comprises a spring-actuated dog 159 pivoted to the opposite end of the arm 154. The dog 159 is adapted to engage an abutment shoulder or notch 161 provided at one end of a sleeve 162 secured to one of the hubs 124 of the spout member 121, as best shown in Figure 26. When the spout members 121 and 122 are moved into bag receiving position, as shown in Figures 16, 19, and 20, the dog 159 engages the abutment 161 and retains the movable jaw 144 in its open position, whereby a wall of the bag may be received between the gripping surface 147 of the spout member 121 and the movable jaw 144. The dog 159 is actuated to release the jaw 144, when the cam 133 travels slightly beyond the position shown in Figure 19, or until the roller 132 reaches the lowermost point in the cam. When the roller 132 reaches the lowermost point in the cam, a fixed arm 163, shown in Figures 20, 21, and 24 is engaged by the opposite end of the dog 159, as shown in Figure 20, and moves said dog out of engagement with the notch or shoulder 161, as shown in Figure 21, whereby the spring 157 will swing the movable jaw 144 into gripping engagement with its complementary gripping surface 147,

thereby to grip the wall of the bag therebetween, as shown in Figure 21.

When the movable jaw has been moved into gripping engagement with the bag wall, shown in Figure 21, the spout members 121 and 122 are operated to swing the bag into position to receive a charge, as shown in Figures 10, 11, and 25, as hereinbefore stated.

Filled bag receiving means

10 The means for receiving the filled bags from the filling spout 16 is shown comprising an endless conveyer belt 164 mounted on suitable rolls 165 and 166, supported in a suitable frame structure, generally designated by the numeral 167. The conveyer belt 164 is disposed directly beneath the filling spout, whereby when the filled bags are released therefrom, they will drop onto the conveyer belt in an upright position, as will readily be understood by reference to Figures 1 and 2.

15 The receiving conveyer is provided with a side wall 168 secured to upright posts 169. Guide members 171 are secured to the posts 169 above the guide wall 168 and engage the bodies of the bags, when the latter are supported on the filling spout, and whereby the filled bags, when released from the spout, will drop directly onto the conveyer belt.

20 A suitable conveyer 172 may be connected to the conveyer 164 for conveying the filled bags to a suitable bag settling and closing machine, not shown in the drawings.

Driving mechanism

25 35 The various mechanisms of the machine may be driven from a suitable motor 174 mounted in the lower portion of the machine frame, as shown in Figures 1 and 2. A suitable gear reducer 175 is shown connected to the motor 174, and has a belt drive 176 connecting it to a counter shaft 177 mounted in suitable bearings provided in the machine frame. The shaft 178 of the conveyer 164 is operatively connected to the counter shaft 177 by a suitable gear drive, indicated at 179 in Figure 1. The main operating shaft 44 is shown driven from the counter shaft 177 by a chain drive 181.

40 45 Another feature of the apparatus herein disclosed resides in the means provided for controlling the operation of the weighing mechanism in timed relation to the operation of the main operating shaft, whereby should the bag feeding mechanism fail to deliver a bag to the filling spout, the weighing hopper will not deliver a charge to the filling spout.

50 55 The means provided for thus automatically interrupting the delivery of a charge to the filling spout in the event of bag failure, is best shown in Figures 1, 2, 11, and 12, and comprises a counter shaft 182 mounted in suitable bearings 180 provided in the upper portion of the machine frame, as shown in Figures 1, 2, and 12. The shaft 182 is driven from the main operating shaft by a chain drive 183, whereby the shaft 182 rotates continuously with the main operating shaft 44.

60 65 When two complete bag feeding and filling mechanisms are provided, as herein shown, two independent weighing mechanisms 118 are of course, utilized, one for each bag feeding mechanism. The operations of the two weighing mechanisms are controlled entirely by the feeding of the bags from the magazines to the filling spouts. In other words, the two weighing hoppers are arranged to alternately operate to deliver charges of material into the empty bags

Operation

without interruption, as long as the bags are fed to the filling spouts. Should one of the filling spouts, however, fail to receive a bag from its respective bag feeding mechanism, its respective weighing mechanism is rendered inoperative to deliver a charge into the bagless filling spout.

The means provided for thus controlling the operation of the weighing mechanisms by the feeding of the bags from the magazines to the filling spouts, is best shown in Figures 1, 11, 12, and 24, and comprises a pair of suitable clutches, generally designated by the numerals 184 and 185. These clutches operate to drivingly connect the chain drives 186 of the weighing mechanisms to the clutch shaft 182. The clutches 184 and 185 are similar in construction, and but one will therefore be described in detail. The clutches may be of any suitable type, applicable for the purpose. Each clutch is shown comprising a dog 187 which normally is retained in the position shown in Figure 11. When thus positioned, the two clutch members, indicated by the numerals 188 and 189, are operatively connected together for rotation as a unit, whereby the weighing mechanism associated therewith will operate to deliver one charge during each cycle of operation of the machine. Each clutch further is provided with an operating finger 191, as best shown in Figures 11 and 12. This finger is shown secured to one end of a rock shaft 192 mounted in suitable bearings provided in the upper portion of the machine frame. A relatively short arm 193 is secured to the opposite end of the rock shaft 192 and has one end of a connecting rod 194 connected thereto. The lower end of the connecting rod 194 is connected to an arm 195 shown secured to a short shaft 196 mounted in a bearing 197 secured to one of the side members of the machine frame. A control finger 198 is secured to the lower end of the shaft 196 and extends inwardly to a position to be engaged by the bags 126, as they are fed from the magazine to the filling spout, shown in Figure 24.

The operation of the clutch therefore, is dependent entirely upon the passage of the empty bags from the magazine to the filling spout. The clutch is so constructed that the dog 187 must be operated for each revolution of the clutch in order to operate the weighing mechanism. The clutch finger 191 and dog 187 are therefore so arranged that the finger 191 must be moved out of the path of the dog 187 each time a bag is fed to the filling spout in order that the weighing mechanism will operate to deliver a charge into the bag supported on the filling spout. If a bag fails to actuate the control finger 191, the clutch finger 191 will remain in the full line position shown in Figure 11, whereby it will engage the dog 187 and thereby render the weighing mechanism inoperative. The clutch dog 187 rotates with the part 188 of the clutch which, as will be understood by reference to Figure 12, rotates continuously with the drive chain 183 as long as the machine is in operation. The dog 187 is actuated by the clutch finger 191 each time the clutch shaft 182 makes one revolution, provided, of course, the bags are successively delivered to the filling spout without interruption. Should the bag feeding mechanism fail to deliver a bag to the spout, as hereinbefore stated, the clutch finger 191 is moved out of the path of the clutch dog 187, whereby the clutch will fail to function. The clutch 184 is of the one-revolution type, whereby the weighing mechanism is operated, once for each revolution thereof.

In the operation of the novel apparatus herein disclosed, a plurality of empty bags are placed in the magazine in superposed relation, as shown in Figure 10, with their flat bottoms facing upwardly. The machine is then started, whereupon the plate element 33 is actuated to inwardly press and bend the bag tops, as shown in Figure 5, whereby the mouth of the lowermost bag is partially opened to permit the gripper plate 30 and the bag mouth opener blade 77 to enter the bag mouth. In the next operation, the gripper blade 30 is moved downwardly as a result of the arm 65 being actuated by the cam 67, as shown in Figure 10, until the bottom wall of the lowermost bag is gripped between the gripper blade 30 and the gripper block or surface 74 carried by the drum. Because of the cylindrical surface of the cam 67, the gripper blade 30 will be retained in the position shown in Figures 10 and 11, while the bag is being withdrawn from the magazine and around past the bottom "breaker" hooks 92 and the pressure roller 102, until the bag top reaches substantially the position shown in Figure 16, wherein the bag opener blade 77 is actuated by the bell crank 85, as a result of the button 83 engaging the upper end of the push rod 79. When the bag mouth reaches the position shown in Figure 16, the filling spout members 121 and 122 will be positioned as shown in this same figure, whereby the open bag mouth may readily be pulled over the filling spout members 121 and 122, with a wall of the bag mouth inserted between the jaw 144 and the gripping surface 147, as shown in Figures 19 and 20. When the bag mouth is thus positioned over the filling spout members 121 and 122, as shown in Figure 21, the movable jaw 144 is released, as a result of the dog 159 engaging the member 163, whereupon the wall of the bag top positioned between the gripping surface 147 and the jaw 144 will be firmly gripped therebetween. The cam mechanism then returns the spout members 121 and 122 to their operative positions shown in Figures 10, 11 and 25, whereby said members are separated or moved into open positions against the walls of the bag mouth, thereby cooperating with the movable jaw 144 to secure the bag top to the lower end of the filling spout. It is to be understood that when the spout members 121 and 122 are in the positions shown in Figure 10, the adjusting nut 142 of the spring-actuated bolt 139 will be out of engagement with the cylindrical housing 141, whereby the bag top will be held taut by the tension of the spring 140 of the bolt 139. When the bag is thus supported on the lower ends of the spout members 121 and 122, it will be noted that the lower end of the flexible porous filling tube 114 is positioned within the mouth of the bag so that when the charge of material is delivered into the tube from the hopper 117 of the weighing mechanism, it will be directed into the empty bag body without "puffing". The weighing mechanism, as hereinbefore stated, is controlled by the bag engaging the clutch control finger 198, as will be understood by reference to Figures 11 and 24. As soon as a charge has been delivered into the bag, the cam 153 engages the roller 152 of the arm 148 and thereby actuates the parts shown in Figures 20 and 21, to reset the movable jaw 144 in its open position, as shown in Figure 20. In other words, actuation of the arm 148 by the cam 153 will oscillate the arm 154 in a manner

to permit the dog 159 to again engage the abutment shoulder 161 and thereby lock the movable jaw 144 in open position.

When the movable jaw is thus actuated to release the bag, the filled bag drops by gravity onto the conveyer 164 which, in turn, discharges the filled bag onto the conveyer 172, indicated in Figure 2.

When two complete bag filling and feeding mechanisms are utilized, as shown in Figure 2, they are so timed with respect to one another that they will alternately deliver the bags onto the conveyer 164 in spaced relation. If desired, they may be so adjusted as to deliver the bags onto the conveyer in pairs, as indicated in Figure 2.

We claim as our invention:

1. In a machine of the class described, a magazine for supporting a stack of flat empty bags in superposed relation, said bags having their bottoms disposed in flatwise relation to their respective bag bodies and facing upwardly in the magazine, a rotatable bag feed drum, said drum having complementary gripping elements mounted thereon for engaging the lowermost bag in the magazine when the drum is rotated and withdrawing it therefrom, means operatively connected to said drum for engaging the leading edge of the bottom of said bag and folding said bottom upon a line transverse to the vertical axis of the bag body, whereby the bag body will assume its proper shape, when a charge is delivered thereto.

2. In a machine of the class described, a magazine for supporting a stack of flat empty bags in superposed relation with the intermediate portions of the top ends of the bags unsupported, said bags having their bottoms disposed in flatwise relation to their respective bag bodies and facing upwardly in the magazine, a rotatable bag feed drum, said drum having complementary gripping elements mounted thereon for engaging a wall of the lowermost bag in the magazine when the drum is rotated and withdrawing said bag therefrom, and means operatively connected to said drum for engaging the leading edge of the bottom of said bag and folding said bottom upon itself, thereby to facilitate filling the bag.

3. In a machine of the class described, a magazine for supporting a stack of flat empty bags in superposed relation with the intermediate portions of the top ends of the bags unsupported, said bags having their bottoms disposed in parallel relation to their respective bodies and facing upwardly in the magazine, a filling spout, a rotatable bag feed drum having complementary gripper elements adapted to engage the bottom wall of the lowermost bag in the magazine when the drum is rotated and withdraw said bag therefrom, and means mounted in operative relation to the drum adapted to engage the leading edge of the bottom of said bag and fold it upon itself on a line disposed substantially in the median plane of the bag body, thereby to permit the bag body to readily expand, when a charge is delivered thereto from the filling spout.

4. In a machine of the class described, a magazine for supporting a stack of flat empty bags in superposed relation with the intermediate portions of the top ends of the bags unsupported, said bags having their bottoms disposed in parallel relation to their respective bodies and facing upwardly in the magazine, a filling spout, a rotatable bag feed drum having complementary gripper elements adapted to engage the bottom

wall of the lowermost bag in the magazine when the drum is rotated and withdraw said bag therefrom, means mounted in operative relation to the drum adapted to engage the leading edge of the bottom of said bag and fold it upon itself on a line disposed substantially in the median plane of the bag body, thereby to permit the bag body to readily expand, when a charge is delivered thereto from the filling spout, and means for opening the mouth of the empty bag to facilitate entrance of the filling spout therein.

5. In a machine of the class described, a magazine for supporting a stack of flat empty bags in superposed relation with the intermediate portions of the top ends of the bags unsupported, a plate element movably supported adjacent to the top ends of the bags adapted to engage the unsupported top end of the upper wall of the lowermost bag and inwardly press it to partially open the mouth of said lowermost bag, a filling spout, a rotatable feed drum having cooperating gripper elements adapted to engage the bottom wall of the lowermost bag in the magazine when the drum is rotated and withdraw said bag therefrom, means for breaking the bag bottoms as the bags are successively fed from the magazine to the filling spout by said drum, means for opening the mouth of each empty bag as the bags approach the filling spout, thereby to facilitate entrance of the filling spout therein, and gripper means on the filling spout adapted to engage a wall of the bag top and support the bag on the filling spout, independently of the gripper means on the drum, during the filling operation.

6. In a machine of the class described, a magazine for supporting a stack of flat empty bags in superposed relation with the intermediate portions of the top ends of the bags unsupported, a plate element movably supported adjacent to the top ends of the bags adapted to engage the unsupported top end of the upper wall of the lowermost bag and inwardly press it to partially open the mouth of said lowermost bag, a filling spout, a rotatable feed drum having cooperating gripper elements adapted to engage the bottom wall of the lowermost bag in the magazine when the drum is rotated and withdraw said bag therefrom, means for folding the bag bottoms transversely to the axes of the bag bodies, as the bags are successively fed from the magazine to the filling spout by said drum, means for opening the mouth of each empty bag as the bags approach the filling spout, thereby to facilitate entrance of the filling spout therein, gripper means on the filling spout adapted to engage a wall of the bag top and support the bag on the filling spout independently of the gripper means of the drum, during the filling operation, and means for subsequently actuating the gripper means on the filling spout to release the filled bag therefrom.

7. In a machine of the class described, a magazine for supporting a stack of flat empty bags in superposed relation with the intermediate portions of the top ends of the bags unsupported, a plate element movably supported adjacent to the top ends of the bags adapted to engage the unsupported top end of the upper wall of the lowermost bag and inwardly press it to partially open the mouth of said lowermost bag, a collapsible filling spout, a rotatable feed drum having cooperating gripper elements adapted to engage the bottom wall of the lowermost bag in the magazine when the drum is rotated and withdraw said bag therefrom, means for breaking the bag bot-

toms as the bags are successively fed from the magazine to the filling spout by said drum, means for opening the mouth of each empty bag as the bags approach the filling spout, thereby to facilitate entrance of the collapsed filling spout in the bag mouth, means for expanding the filling spout into engagement with the bag mouth walls, and gripper means on the filling spout adapted to engage a wall of the bag top and support the bag on the filling spout, during the filling operation.

8. In a machine of the class described, a magazine for supporting a stack of flat empty bags in superposed relation, a plate element movably supported adjacent to the top ends of the bags adapted to engage the top end of the upper wall of the lowermost bag, to partially open the mouth of said lowermost bag, a filling spout, a rotatable feed drum having cooperating gripper elements

adapted to engage the bottom wall of the lowermost bag in the magazine when the drum is rotated and withdraw said bag therefrom, means for folding the bag bottoms transversely to the axes of the bag bodies, as the bags are successively fed from the magazine to the filling spout by said drum, means for opening the mouth of each empty bag as the bags approach the filling spout, thereby to facilitate entrance of the filling spout therein, gripper means on the filling spout adapted to engage a wall of the bag top and support the bag on the filling spout independently of the gripper means of the drum, during the filling operation, and means for subsequently actuating the gripper means on the filling spout to release the filled bags therefrom.
